UNITED STATES PATENT OFFICE.

ISAAC W. BIRDSEYE, OF BRIDGEPORT, CONNECTICUT.

CORSET.

SPECIFICATION forming part of Letters Patent No. 357,362, dated February 8, 1887.

Application filed August 23, 1886. Serial No. 211,578. (No model.)

To all whom it may concern:

Be it known that I, ISAAC W. BIRDSEYE, a citizen of the United States, residing at Bridgeport, in the county of Fairfield and State of Connecticut, have invented certain new and useful Improvements in Corsets; and I do hereby declare the following to be a full, clear, and exact description of the invention, such as will enable others skilled in the art to which it applies to make and use the same.

My invention relates to the manufacture of corsets, and has for its object to simplify and cheapen and in a general way to improve the details of their construction.

With these ends in view I have devised the novel corset of which the following description, in connection with the accompanying drawings, is a specification, numbers being used to indicate the several parts.

Figure 1 is an elevation of the half-corset complete; Fig. 2, a cross-section on the line *x x*; Fig. 3, a cross-section of the bust-piece on the line *y y*; Fig. 4, a vertical section of the bust-piece on the line *z z*, and Fig. 5 is a section across the waist-stay on the line *k k*.

1 is the front section, which contains the front stay or steel; and 2, the back section, which contains the lacing-stay. So far as my present invention is concerned these two sections may be made in any suitable or preferred form, and may or may not contain cords 3. I preferably, however, cord them, as shown, and secure the stays and cords in position by vertical seams 4. The edges of these sections are turned under, and the edges of the next sections are placed between them and secured thereby by seams 4.

5 denotes corded sections, which extend across each half-corset from top to bottom. The edges of these sections are turned under in the same manner as the edges of sections 1 and 2, and the next sections are secured between these edges by vertical seams 4, as already described.

An important feature of my improved construction is, that between the corded sections I place sections or pieces 6, which may of course be single or double. I preferably, however, make them single, as shown in Figs. 4

and 5. These sections do not extend from top to bottom of the corset, but extend, respectively, from the top and bottom, and are joined at their inner ends to short double cross-sections 7, which constitute the waist-stay of the corset. The construction of the sections 7 of the waist-stay is clearly illustrated in Fig. 2. The opposite ends of these sections are secured between the edges of corded sections 5 by vertical seams 4. The top and bottom edges of sections 7 are turned inward, as shown in Fig. 6, and the respective ends of short sections 6 are secured between them by short cross-seams 8.

It will thus be seen that my improved construction enables me to make a large portion of each half-corset of small pieces of material, thus effecting a great saving in material and utilizing numerous small pieces that would otherwise be thrown away. I furthermore secure the greatest possible strength at the waist of the corset, where most strength is needed, by stitching each end of double sections 7, constituting the waist-stay, to double-corded sections 5.

The bust-pieces I form in the following manner: In order to give strength and firmness to the upper portions thereof, I form them of short double-corded sections 9, the opposite ends of which are secured to vertical corded sections 5 by seams 4. The lower edges of cross-sections 9 are turned inward, as shown in Fig. 4, and pieces or strips 10 are secured between said edges by short cross-seams 11. Strips 10 extend from the bottom of cross-section 9 to the bottom of the corset, as clearly shown in Fig. 1. These sections, as well as section 6, may be made single or double, and are so curved as to give the desired shape or fit to the corset, their edges being secured to double-corded sections by vertical seams 4.

It will of course be understood that the details of construction may be varied within reasonable limits without departing from the spirit of my invention.

I claim—

The herein-described corset, consisting of front and back sections, intermediate corded

sections, 5, short double cross sections 7, constituting the waist-stay and connecting a portion of the vertical sections, short single sections 6, inserted between the double, vertical, 5 and cross sections, and bust-pieces consisting of short corded cross-sections 9 and strips 10, which extend from the bottom of sections 9 to the bottom of the corset, substantially as described.

In testimony whereof I affix my signature in presence of two witnesses.

ISAAC W. BIRDSEYE.
